DESIGN FOR WEBBING

Application filed March 4, 1932. Serial No. 43,068. Term of patent 7 years.

To all whom it may concern:

Be it known that I, FREDERICK J. ZIMMERER, Jr., a citizen of the United States, and a resident of Middletown, in the county of Middlesex and State of Connecticut, have invented a new, original, and ornamental Design for Webbing, of which the following is a specification, reference being had to the accompanying drawing, forming part thereof, in which—

Figure 1 is a face view of a piece of webbing embodying my invention.

Figure 2 is a fragmental face view on enlarged scale.

I claim:

The ornamental design for webbing as shown.
